PROTECTIVE MEANS FOR ELECTRIC FURNACES

Filed Sept. 10, 1925

Inventor:
Albert N. Otis,

by *Maurand S. Lunt*
His Attorney.

UNITED STATES PATENT OFFICE.

ALBERT N. OTIS, OF SCHENECTADY, NEW YORK, ASSIGNOR TO GENERAL ELECTRIC COMPANY, A CORPORATION OF NEW YORK.

PROTECTIVE MEANS FOR ELECTRIC FURNACES.

Application filed September 10, 1925. Serial No. 55,584.

My invention relates to protective means for electric furnaces, and has for its object the provision of improved means for opening the heating circuit of the furnace upon the occurrence of a predetermined maximum temperature therein.

More specifically, my invention relates to protective means for high temperature electric furnaces such as are used, for example, in the heat treatment of metals for annealing and hardening purposes, etc. Such furnaces are ordinarily provided with a resistance heater and operate at temperatures around 900° C., which is near the maximum safe working temperature of the resistor so that care must be taken to prevent damage to the resistor by overheating. One form of protective means for furnaces of this type, in the nature of a fuse, is described and claimed in Patent No. 1,490,408 to Van Aller, dated April 15, 1924, of which my invention is an improvement. In such devices the protective means may be inserted through a suitable aperture in the furnace wall so as to be exposed to the heat of the furnace.

In carrying out my invention, I provide an elongated support made of insulating material and provided with longitudinal apertures through which a fuse wire is threaded in such manner that the ends of the fuse wire are at the outer ends of the support and the central portion of the fuse wire at the inner end of the support is exposed to the heat of the furnace.

For a more complete understanding of my invention reference should be had to the accompanying drawing in which Fig. 1 is a plan view of protective means embodying my invention; Fig. 2 is an enlarged fragmentary sectional view of the device shown in Fig. 1 taken along the line 2—2 of Fig. 4 looking in the direction of the arrows; Fig. 3 is a fragmentary sectional view taken along the line 3—3 of Fig. 4 looking in the direction of the arrows; Fig. 4 is an end view with the cover removed; Fig. 5 is a detail view; while Fig. 6 is a diagrammatic view showing the application of my invention to an electric furnace.

Referring to the drawing, I have shown my invention in one form as comprising a plurality of members or blocks 10 which may be cylindrical in form, and which are made of suitable insulating material such as porcelain. These insulating members are similar in construction and are each provided with four longitudinal apertures 11, 12, 13 and 14

(Fig. 5) spaced at equal intervals around their peripheries. The apertures 11 and 13 are somewhat larger than the apertures 12 and 14, and are adapted to receive a U shaped clamping member or rod 15 which is threaded through these apertures in a series of the insulating members 10 so as to hold them in end to end abutting relation, as indicated in Fig. 2. Preferably, a specially formed insulating member 16 is provided at the end, which member is slipped on the clamping rod 15 first, this insulating member being provided with a transverse groove 17 which connects its apertures 11 and 13 and in which the transverse central portion 18 of the supporting rod lies. After the insulator 16 has been slipped on the clamping rod, the desired number of insulators 10 are slipped on together with a specially formed insulating member 19 at the opposite or outer end. This member 19 is likewise provided with apertures 11, 12, 13 and 14, and after it is put in place washers are placed over the threaded ends of the clamping rod 15 and nuts 20 and 21 applied and turned down tightly so as to securely clamp the various insulating members together and thereby form a rigid elongated insulating support.

The outer insulating member 19 is cylindrical in shape, but, as shown in Fig. 2, is considerably larger in diameter than the insulators 10 whereby a metallic casing or head member 22 may be secured by clamping it to a metallic ring 23 which is slipped over the insulators 10 and seated against the ledge formed by the projecting edge of the insulator 19. Metallic connector members 24 and 25 (Fig. 3) are seated in longitudinal apertures in the insulator 19, these members being provided with central longitudinal apertures 26 and 27 which correspond with the apertures 12 and 14 of the insulators 10. Suitable clamping screws 28—31 inclusive are provided in the connectors 24 and 25, transverse openings being provided in the insulator 19 so that access may be had to these clamping screws by removing the cover 22.

It will be observed that the aligned apertures 12 form a continuous duct leading longitudinally throughout the entire length of the fuse support and likewise the aligned apertures 14 form a similar longitudinal aperture. A fuse wire 32 is threaded through these longitudinal apertures, it being substantially U shaped with its central portion extending across the inner end of the support,

i. e., across the end of members 16, and its ends lying in the connectors 24 and 25 in which they are secured by means of the screws 28 and 31 in electrically conducting relation with the connectors. It will be understood that the fuse wire may be formed of different metals, the central exposed portion being made of a metal having the desired melting point. Preferably, an insulating bead 33 is placed on the fuse wire at its central portion. This bead drops upon softening of the fuse wire and thereby positively opens the electric circuit through the fuse wire. Conductors 34 and 35 are connected to the ends of the fuse wire by means of the connectors 24 and 25 whereby the fuse wire may be included in a suitable control circuit. The head 22 is provided with a narrow neck 36 through which the electrical conductors are inserted, a suitable insulator 37 being provided. The upper or outer end of the insulator 19 is provided with a recess 38 to provide space for the clamping nuts 20 and 21 and likewise for the conductors 34 and 35.

As shown in Fig. 6, the fuse may be connected in circuit with the operating coil 39 of an electric switch 40 which is in circuit with the heating resistor 41 of the furnace whereby the resistor is disconnected from its supply source 42 upon the occurrence of a predetermined maximum temperature by reason of the melting of the inner portion of the fuse wire which opens the circuit of the operating coil 39.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States is:

1. A protective device for electric furnaces comprising an elongated heat refractory electrically insulating support provided with longitudinal apertures, said support being adapted to be inserted in an aperture in the furnace wall, and a wire threaded through said apertures having its ends at the outer end thereof and having a fusible portion extending across the inner end of said support so as to be exposed to the heat of said furnace.

2. A protective device for electric furnaces comprising a plurality of heat refractory

electrically insulating members provided with apertures, means for securing said members in abutting relation with their apertures registering so as to form an elongated heat refractory insulating support adapted to be inserted in an aperture in a furnace wall, and a fuse wire threaded through said apertures having its ends at the outer end of said support, and a central portion extending across the inner end of said support so as to be exposed to the heat of the furnace.

3. A protective device for electric furnaces comprising a plurality of insulating members provided with apertures, clamping means extending through some of said apertures to secure said members together in abutting relation and thereby form an elongated self supporting insulating support adapted to be inserted in an aperture in a furnace wall, and a fuse wire threaded through the remaining apertures in said members having a portion exposed to the heat of said furnace at the inner end of said support.

4. A protective device for electric furnaces comprising a plurality of insulating members provided with apertures, a U shaped clamping rod threaded through two of the apertures of said members so as to secure said members together in abutting relation and thereby form an elongated insulating support adapted to be inserted in an aperture in a furnace wall, and a fuse wire threaded through the remaining aperture in said members having a portion extending across the inner end of said support so as to be exposed to the heat of said furnace.

5. A protective device for electric furnaces comprising a plurality of insulating members, each of said members being provided with four spaced apertures, a U shaped clamping rod threaded through two of said apertures so as to secure said members in abutting relation and thereby form an elongated insulating support adapted to be inserted in an aperture in a furnace wall, a fuse wire threaded through the remaining two of said apertures so that its ends are at the outer end of said support and a central portion extending across the inner end of said support so as to be exposed to the heat of the furnace, electrical connectors secured to the ends of said fuse wire whereby said fuse wire is included in a circuit to be controlled, and a metallic protecting head secured to the outer end of said support.

In witness whereof, I have hereunto set my hand this 9th day of September, 1925.

ALBERT N. OTIS.
